UNITED STATES PATENT OFFICE.

HERMAN SCHREIBER, OF DUNKIRK, INDIANA, ASSIGNOR TO THE OHIO FLINT GLASS COMPANY, OF SAME PLACE.

GLASS-FINISHING MACHINE.

SPECIFICATION forming part of Letters Patent No. 623,291, dated April 18, 1899.

Application filed December 19, 1898. Serial No. 699,723. (No model.)

To all whom it may concern:

Be it known that I, HERMAN SCHREIBER, a resident of Dunkirk, in the county of Jay and State of Indiana, have invented a new and useful Improvement in Glass-Finishing Machines; and I do hereby declare the following to be a full, clear, and exact description thereof.

My invention relates to glass-finishing apparatus.

The object of my invention is to provide a compact, simple, and convenient form of glass-finishing apparatus in the operation of which the articles to be finished may be handled and finished in quick succession and the work accomplished with greater uniformity and more perfectly.

To these ends my invention comprises the novel features hereinafter set forth and claimed.

To enable others skilled in the art to make and use my invention, I will describe the same more fully, referring to the accompanying drawings, in which—

25 Figure 1 is a side view of my improved apparatus. Fig. 2 is a view of the opposite side. Fig. 3 is a section on line 3 3, Fig. 1. Fig. 4 is an enlarged vertical section of the burner, and Fig. 5 is a plan view of the burner removed.

Like letters indicate like parts in each of the figures.

The letter *a* in the drawings designates a bed or support upon which my improved finishing apparatus is mounted, and as said bed is preferably mounted on wheels I have illustrated it as so mounted. It is thus capable of being quickly moved from one part of the factory to another.

40 Supported by the bed *a* are the uprights *b*. At the upper ends of the uprights *b* are the brackets *c c'*, the bracket *c* forming part of the ring *d* and having an opening through which the upright *b* passes, so that said bracket is capable of being moved up and down on said upright. The set-screw *e* acts to secure the bracket to said upright when it has been adjusted at the proper height. The bracket *c'* has an opening through which the upright *b* passes and is also vertically adjustable on

said upright, being provided with the set-screw *f*. The bracket *c'* projects out and supports the front of the ring *d*.

The ring *d* is provided with the inwardly-extending flange *d'* and the outwardly-extending flange *d''*, said flanges forming a suitable seat for the reception of the "glory-hole" *H*. This glory-hole *H* may be formed of fire-clay or other suitable refractory material and has the neck *h*, which fits down 60 within the ring *d* and rests upon the flange *d'*, while the shoulder *h'* rests upon the flange *d''*.

The glory-hole *H* has the conical opening *h''*, and at the lower or larger portion of said opening is the burner *g*, encircling said opening. The glory-hole is slightly recessed or grooved, as at *h''*, to receive the burner, and said burner is secured therein in any suitable manner.

The body of the burner *g* is circular in form and is provided with the apertures *g'*. The straight extension *g''* of the burner *g* projects out through an opening in the ring *d*, and to said extension is connected the gas-supply pipe *g''*, by which gas is supplied to said burner.

75 The walls of the glory-hole *H* just above the conical opening *h''*, are provided with the apertures *h''*, by means of which the waste products of combustion escape to the space *i*, formed between the glory-hole and the outer dome *k*. This outer dome *k* may also be formed of fire-clay, and it has the escape-flue *k'*, to which a suitable chimney *m* may be connected.

In alignment with the opening *h''* of the glory-hole *H* is the sleeve *n*, said sleeve being mounted on the bed *a* and around the opening *n'* in said bed. A vertically-movable rod *o* is contained within the sleeve *n*. At the upper end of said rod *o* is the socket *o'* or seat *o'*, adapted to receive the shank *r'* of the former *r*. The shank *r'* has the annular groove *r''*, which forms a seat for the entrance of the tool used for placing the shank in the socket *o'* and removing it therefrom. The former illustrated is one adapted to receive a glass dish *r''*; but formers of different shapes may of course be employed. At the lower end of the rod *o* is the cross-bar *s*, to each end of which is secured a chain *s' s''*. These 100

chains pass up through openings t in the bed a , over idle pulleys t' , and down through openings t'' . Weights t^3 are secured to the ends of said chains. In this manner the rod o is counterbalanced, and its vertical movement is more easily effected. A lever or handle u is secured to the rod o , said lever working in a vertical slot n^2 in the sleeve n . The outer end of lever u works in a guide u' on the upright v . Notches v' are formed on the upright v within the guide u' to support the lever u at different heights, according to the position of the rod o with reference to said glory-hole.

15 While I have described only one glory-hole and its connections, one vertically-movable rod, &c., yet the drawings show all the parts in duplicate, and the apparatus is preferably constructed in this form, although it is of course apparent that the number of glory-holes may be increased, if desired.

I do not wish to limit myself to the exact construction shown, as that may be varied without affecting the scope of my invention.

25 The operation of my improved glassware-finishing apparatus is as follows: The gas is turned on at the valves of the supply-pipe, and the gas is ignited at the burners g . The products of combustion rise within the vaulted glory-hole and thoroughly heat same before they find their way out through the apertures h^4 . The conical-shaped opening h^2 directs the heated products toward the center of the glory-hole, where the most intense heat is desired. When the glory-hole has been properly heated, the operator, with the former r in position to receive the dish r^3 , receives said dish thereon in its inverted form from the boy who brings it directly from the press. The former is lifted and its shank r' is placed in the socket o' of the rod o , said rod having been lowered by the lever u to the position shown in Fig. 1. Having mounted the former carrying the dish on the rod o , 40 the operator grasps the lever u and raises said rod until the former passes up through the opening h^2 into the glory-hole. The dish is then subjected to the intense heat of the glory-hole, and the edges of said dish are in 45 the direct path of the heat as it comes from the burner. As the edge of the dish around its entire circumference is exposed to the same heat, the finishing is uniform and perfect, and no rotation of the rod carrying the 50 dish is necessary. The circular burner distributes the heat evenly, so that no part is more highly heated than another.

55 Where two glory-holes are mounted on the same bed, as illustrated, the operator can arrange to have one of the rods elevated, so as to bring the dish within the glory-hole while he lowers the other rod, removes the finished dish with the former, and places another former in the socket of the lowered rod, said 60 rod being supported by the lever u , engaging the notches in the guide u' . This rod is then

elevated and the other one lowered. In this manner in quick succession the dishes are finished as they are carried from the presser.

By my invention I provide a glass-finishing apparatus in which the glory-hole and the devices for introducing the articles of glassware thereto and withdrawing them therefrom are so combined as to form a simple, compact, and conveniently-handled apparatus which will give greater uniformity and a better-finished product. -

What I claim as my invention, and desire to secure by Letters Patent, is—

1. In glass-finishing apparatus, the combination with a suitable support, of an upright rod on said support, a glory-hole mounted on said upright rod and vertically adjustable thereon, said glory-hole having an opening in the bottom thereof, and a vertically-movable 85 rod in line with said opening adapted to support the article of glassware, substantially as set forth.

2. In glass-finishing apparatus, the combination with a suitable support, of an upright 90 rod on said support, a vertically-adjustable ring carried by said rod, and a glory-hole mounted on said ring, said glory-hole having an opening in the bottom thereof, and a vertically-movable rod in line with said opening 95 adapted to support the article of glassware, substantially as set forth.

3. In glass-finishing apparatus, the combination with a suitable support, of an upright rod on said support, a vertically-adjustable 100 bracket on said upright rod, a ring on said bracket, and a glory-hole mounted on said ring, said glory-hole having an opening in the bottom thereof, and a vertically-movable rod 105 in line with said opening adapted to support the article of glassware, substantially as set forth.

4. In glass-finishing apparatus, the combination with a suitable support, of an upright rod on said support, a bracket vertically adjustable on said rod, a ring on said bracket, said ring having an inwardly-extending flange around its central opening, and a glory-hole having a neck fitting down within said ring and resting on said flange, said glory-hole having an opening in the bottom thereof, and a vertically-movable rod in line with said opening 115 adapted to support the article of glassware, substantially as set forth.

5. In glass-finishing apparatus, the combination with a suitable support, of an upright 120 on said support, a slidable bracket on said support, a set-screw adapted to secure said bracket to said upright, a ring on said bracket, and a glory-hole mounted on said ring, said 125 glory-hole having an opening in the bottom thereof, and a vertically-movable rod in line with said opening adapted to support the articles of glassware, substantially as set forth.

6. A glory-hole for finishing articles of 130 glassware comprising a dome-shaped chamber with a central charging-opening in the

bottom thereof through which the article to be finished is inserted, and a burner surrounding said opening.

7. A glory-hole for finishing articles of 5 glassware, comprising a dome-shaped chamber having a central charging-opening in the bottom thereof through which the article to be finished is inserted, the walls of said opening tapering from the outer to the inner end 10 thereof, and a burner surrounding the lower end of said opening, substantially as set forth.

8. A glory-hole for finishing articles of 15 glassware comprising a dome-shaped heating-chamber and a central charging-opening in the bottom thereof through which the article to be finished is inserted, a gas-burner surrounding said opening, a dome-shaped hood inclosing said glory-hole, space being left between said hood and the outer walls of said 20 glory-hole, the walls of said glory-hole hav-

ing openings leading to said space, and said hood having an escape-flue, substantially as set forth.

9. A glory-hole having a central charging-opening in the bottom thereof through which 25 the article to be finished is inserted, a gas-burner surrounding said opening, said glory-hole having a dome-shaped heating-chamber with openings around the base of said dome, and a hood encircling said glory-hole with 30 space between said hood and the outer walls of said glory-hole, said hood having an escape-flue, substantially as set forth.

In testimony whereof I, the said HERMAN SCHREIBER, have hereunto set my hand.

HERMAN SCHREIBER.
